Filed Sept. 26, 1967, Ser. No. 8,748

Term of patent 7 years

Int. Cl. D9—04

U.S. Cl. D9—193

FIG. 2

FIG. 1 is a plan view of a package of candies, showing my new design; and

FIG. 2 is an enlarged fragmentary perspective view showing a portion thereof.

The characteristic features of the design reside in the full line portions, and essentially in the particular arrangement and appearance of the candies as shown. The side opposite that shown in FIG. 1 is substantially similar thereto.

I claim:

The ornamental design for a package of candies, substantially as shown and described.
